UNITED STATES PATENT OFFICE.

FRANK E. MUNN, OF NEW YORK, N. Y.

OPENER FOR ENVELOPS OR WRAPPERS FOR NEWSPAPERS OR THE LIKE.

SPECIFICATION forming part of Letters Patent No. 562,336, dated June 16, 1896.

Application filed April 18, 1896. Serial No. 588,116. (No model.)

To all whom it may concern:

Be it known that I, FRANK E. MUNN, of New York, in the county of New York and State of New York, have invented a new and useful Improvement in Openers for Envelops or Wrappers for Newspapers or the Like, of which the following is a specification.

My invention relates to improvements in openers for envelopes, wrappers and the like, and has for its object to provide an opener of the character indicated, which is equally adapted for envelopes, newspaper-wrappers, wrappers for boxes, parcels, and packages of every description, and boxes themselves.

15 A further object of the invention is to provide an opener, which will virtually form a portion of the envelop, wrapper, or box, being so attached thereto that it can be readily grasped and drawn in direction of one or the 20 other ends or sides of the envelop or wrapper, so as to sever the same and disclose the contents thereof without injury to the same.

The invention consists in the novel construction and combination of the several 25 parts, as will be hereinafter fully described, and pointed out in the claim.

Reference is to be had to the accompanying drawings, forming a part of this specification, in which similar characters of reference indicate corresponding parts in all the figures.

Figure 1 is a rear elevation of an envelop having my improvement applied and illustrating a portion of the opener withdrawn from the envelop and the latter partially 35 opened at that end at which the opener is applied. Fig. 2 is a rear elevation of a portion of an envelop broken away at one end and showing the opener in side elevation. Figs. 3 and 4 are perspective views of newspaper-wrappers having my improvement applied. Figs. 5 and 6 are perspective views of a package and box, respectively, having my improvement applied to the wrappers thereof; and Fig. 7 is a perspective view of a portion of a 45 box to which the improvement is applied.

Referring to Figs. 1 and 2, A represents an envelop, and B the opener located at one end thereof. Instead, however, of arranging the opener at one end of the envelop, as shown, it may be placed at the top or bottom of the envelop or at any other point wherever it may be found desirable.

The opener B consists of a strip or piece of fine wire b, the main portion of which is located within the envelop close to the edge 55 thereof, and the ends of the wire are formed into closed loops b', consisting of three parallel strands, which inclose and lie close to the stock of the envelop.

The loops b' are each formed by passing 60 the end of wire out through the envelop to the exterior thereof, then bending it inwardly to form the member 10, which lies parallel with the body of the wire and on the outside of the envelop, then passing it through the 65 envelop to the interior of the same, and finally bending it outwardly, forming the member 11, which lies within the envelop and parallel with the body of the wire, as clearly shown in Fig. 2.

If in practice it is found desirable, any desired number of loops may be formed in the body portion of the wire between its end loops, or but a single loop may be formed in the wire and visible from the outside of the envelop, 75 the other end of the wire being likewise secured to the envelop.

In Figs. 3 and 4 the opener is shown applied to newspaper-wrappers; in Figs. 5 and 6 to a wrapper for a package and box, respectively; 80 and Fig. 7 to a box itself. In these views the wire is applied and formed with loops similar to those above described with reference to the envelop, and the loops may extend beyond the edges of the same, as shown in Fig. 3 and 85 Fig. 6, or arranged a short distance from said edges, as shown in Figs. 4, 5, and 7 and the right-hand end of Fig. 6.

By securing the wire to an envelop, wrapper, or box as above described, it will be 90 firmly and securely held in place, the formation of the loops effectually preventing it from being accidentally loosened or detached, and owing to the size of the loops, and the fact that they hug the surface of the envelop, wrapper, 95 or box closely, they will not protrude beyond the outer surface thereof to any appreciable extent, and certainly not sufficiently to be caught by any mail-matter, or any object with which the envelop, parcel, box, or package 100 may be brought in contact in transportation or storage.

In operation to open an envelop or wrapper or box all that is necessary is to grasp the ex-

posed member of one of the loops and draw the loop, and by means of it the body of the wire, outward, as shown in Fig. 1, whereupon the body portion of the wire will cut the envelop or wrapper as it frees itself, making a clean cut, and opening the envelop or wrapper of the parcel, box, or package and without injury to the contents thereof.

Having thus described my invention, what I claim, and desire to secure by Letters Patent, is—

The combination with an envelop, wrapper or the like, of an opener, consisting of a fine wire, the main portion of which lies on the in-

side of the envelop or wrapper, each end of the wire being passed outside of the envelop or wrapper, then bent backward and passed inside of the same, and then again bent so as to run parallel with the main portion of the wire, whereby closed loops, consisting of three substantially parallel strands are formed, the strands inclosing and lying close to the stock of the envelop or wrapper, substantially as described.

FRANK E. MUNN.
